(57) **CLAIM**

The ornamental design for a medical head for robotic arm, as shown and described.

DESCRIPTION

FIG. 1 is a front view of a medical head for robotic arm showing our new design within a portion of a robotic arm; FIG. 2 is a back view of the article of FIG. 1 within a portion of a robotic arm;

FIG. 3 is a left view of the article of FIG. 1 within a portion of a robotic arm;

FIG. 4 is a right view of the article of FIG. 1 within a portion of a robotic arm;

FIG. 5 is a perspective view of the article of FIG. 1 within a portion of a robotic arm;

FIG. 6 is a top view of the article of FIG. 1 within a portion of a robotic arm;

FIG. 7 is a bottom view of the article of FIG. 1 within a portion of a robotic arm;

FIG. 8 is an enlarged view of the article of FIG. 1; and, FIG. 9 is an enlarged view of the article of FIG. 1.

The dash-dash broken lines in FIG. 7 define the bounds of the claimed design and form no part thereof. The dot-dash lines in FIG. 7 depict portions of the medical head for robotic arm that form no part of the claimed design. The portions of a robotic arm, shown in dashed lines in FIGS. 1, 2, 3, 4, 5, 6, and 7, are for the purpose of illustrating environment that forms no part of the claimed design.
